UNITED STATES PATENT OFFICE.

THOMAS B. HARRIS, OF JACKSONVILLE, FLORIDA.

GUARD.

1,136,601.

Specification of Letters Patent. Patented Apr. 20, 1915.

Application filed May 16, 1914. Serial No. 839,107.

To all whom it may concern:

Be it known that I, THOMAS B. HARRIS, a citizen of the United States, residing at Jacksonville, in the county of Duval and State of Florida, have invented certain new and useful Improvements in Guards, of which the following is a specification; reference being had to the accompanying drawings.

- 10 This invention relates to certain improvements in guards and has relation more particularly to a device of this general character, especially designed and adapted for use in connection with fire alarm boxes; and an 15 object of the invention is to provide a device of this general character having novel and improved means whereby a signal is caused to be operated when effort is made to gain access within the fire alarm box.
- 20 Furthermore, it is an object of the invention to provide a device of this general character including novel and improved means adapted to normally inclose the lock on the door of the fire alarm box and having 25 normally a single point of entrance for the hand in order to release such lock and whereby such single point or entrance is surrounded by means adapted to engage the hand or arm in such a manner as to maintain 30 the person endeavoring to operate the fire alarm captive.

The invention consists in the details of construction and in the combination and arrangement of the several parts of my improved guard whereby certain important advantages are attained and the device is rendered simpler, less expensive and otherwise more convenient and advantageous for use, all as will be hereinafter more fully set 40 forth.

The novel features of the invention will be carefully defined in the appended claim.

In order that my invention may be the better understood, I will now proceed to 45 describe the same with reference to the accompanying drawings, wherein—

Figure 1 is an elevational view of a fire alarm box, with a guard constructed in accordance with an embodiment of my invention applied thereto, the support for the fire alarm being shown in fragment; Fig. 2 is a side elevational view of my improved guard as shown in Fig. 1, with the adjacent portion of the fire box indicated in section; 50 Fig. 3 is an enlarged sectional view taken substantially on the line 3—3 of Fig. 1; and

Fig. 4 is a sectional view taken substantially on the line 4—4 of Fig. 3.

As disclosed in the accompanying drawings, 1 denotes a fire alarm box of any ordinary or preferred construction, herein disclosed as suitably connected with a supporting standard or post 2. The hinged door 3 of the fire alarm box is provided with any conventional form of locking means, as indicated at 4. The locking means 4 is adapted to be incased within the housing 5 of any desired configuration or dimensions and having its rear face open and being hingedly connected with the door 3, as indicated at 6, 70 while the opposite side of such housing is provided with the projections 7 adapted to be directed through suitable openings 8 produced in the door, such projections terminating in the eyes 9 through which a pin 10 or the like is adapted to be directed in order to normally maintain the housing in assembled position. In order that visual access may be had within the housing, I provide the top and a side wall thereof with an opening 11 80 covered by any suitable transparent member 12, as is believed to be clearly apparent.

In the forward face of the housing in substantial alinement with the lock controlling means 4 is an entrance opening 14 of a size 85 as to permit the insertion therethrough of the hand and arm of a person to an extent as to permit the lock controlling means to be engaged and properly operated and, as herein disclosed, such entrance opening 14 is 90 surrounded by the inwardly directed leaves 15 hingedly connected to the inner face of the outer wall of the housing, as indicated at 16, and these leaves or wings 15 are surrounded by a retractile annular member 95 17 produced preferably from a coil spring possessing the requisite tension, which serves to normally maintain a restricted opening but which will permit the insertion of the hand or arm therethrough. The inner surfaces of the free or inner extremities of the wings are provided with the inwardly directed penetrating teeth 18 which under the influence of the retractile member 17 serve as an effective medium to prevent the withdrawal of the arm or hand and thus holds the person endeavoring to operate the fire alarm captive, in a manner which is believed to be clearly obvious.

In order that a signal may be given immediately adjacent the fire alarm box so that attention of other persons in the vi-

2
 cinity may be attracted, I support within the housing 5 the horizontally disposed tubular member 19, preferably formed of rubber, through which is directed a rod 20 5 adapted for endwise movement therethrough and having one extremity adapted to be operatively engaged by one of the wings or leaves 15, while the opposite extremity of such rod is provided with a contact plate 21 adapted to bridge the contacts 22 interposed in the circuit 23 of the bell 24, herein shown as operatively supported by the post 2. By this arrangement, it will be seen that as the hand is inserted 10 within the entrance opening 14, the resultant movement of the leaves or wings 15 will result in the requisite closing of the circuit 23 and the operation of the signal.

It will be observed that the housing 5 and 20 its position upon the door 3 is such as to in no wise interfere with the person using his other hand for operating the fire alarm mechanism contained within the box 1 and in releasing the rod 10 so that the housing 5 25 may be swung outwardly in order to disengage the wings or leaves 15 so that the hand inserted through the opening 14 may be withdrawn, but it will be observed that the time required for this purpose will be 30 such as to permit the persons attracted by the signal to observe the individual at the box.

In order that the door 3 may be properly relocked and the parts properly reset by an 35 authorized person, I produce in one of the sides of the housing 5 an opening 25 adapted to be closed, as herein disclosed, by the hinged door 26 normally maintained in such closed position by a conventional lock 27.

40 As the source of electrical energy within the circuit 23 may be either from batteries suitably positioned within the housing or from a main line, such source is only diagrammatically indicated at 28.

While I have herein disclosed the signal 45 24 as a bell, it is to be understood that, if desired, a lamp may be employed with equal facility and, if desired, both a bell and a lamp 25^a may be interposed in the circuit 23.

From the foregoing description, it is 50 thought to be obvious that a guard constructed in accordance with my invention is of an extremely simple and comparatively inexpensive nature and is particularly well adapted for use by reason of the convenience and facility with which it may be assembled, and it will also be obvious that my invention is susceptible of some change and modification without material departure 55 from the principles and spirit thereof and for this reason I do not wish to be understood as limiting myself to the precise arrangement and formation of the several parts herein shown in carrying out my invention in practice. 60

65 I claim:

A device of the character described comprising a housing adapted to normally inclose a lock operating mechanism and provided with an entrance opening, contacts 70 within the housing, an electrically operated signal, a circuit for operating said signal, said contacts being interposed in said circuit and normally maintaining the circuit open, an endwise movable rod within the 75 housing provided at one extremity with a contact plate adapted to coact with the first mentioned contacts, and means operable upon the insertion of the hand through the entrance opening to impart movement to 80 the rod in a direction to cause the contact plate to engage the first named contacts.

In testimony whereof I hereunto affix my signature in the presence of two witnesses.

THOS. B. HARRIS.
